(57) **CLAIM**

We claim the ornamental design for a connector, as shown and described.

DESCRIPTION

FIG. 1 is a rear perspective view of the connector showing our new design;

FIG. 2 is a rear view of the connector;

FIG. 3 is a front view of the connector;

FIG. 4 is a left side view of the connector;

FIG. 5 is a right side view of the connector;

FIG. 6 is a top view of the connector; and,

FIG. 7 is a bottom view of the connector.

The broken line portion of the figure drawings is included to show unclaimed subject matter only and forms no part of the claimed design.
